ABSTRACT OF THE DISCLOSURE

Apparatus for separating the copy sheet material from a master after exposure in an exposing station from which the copy sheet and master are guided into a concave surface which causes separation of the master from the copy sheet. The concave surface guides the leading edges of the copy sheet and master over a guiding plate to a gear means which engages the copy sheet arresting the forward motion of the leading edge thereof thereby producing a hump which moves the leading edge of the master away from the copy sheet for easy grasping and separation. The gear means is driven at a slower rate than the leading edge of the copy sheet moves in a direction away from the master.

The present invention relates to copying machines and more particularly to a machine which provides for separation of the master or original from the sensitive copy sheet so that the sensitive copy sheet can be processed to fix the image thereon.

Heretofore photocopying machines have been used in which the master or original is placed in face-to-face contact with a photosensitive copy sheet and actinic light is passed through the master thereby exposing the copy sheet which is then processed to develop and fix the image on the copy sheet. Some difficulty has been experienced in separating the master from the exposed copy sheet and various methods and means have been provided to separate the master from the sensitive copy sheet. One way of doing this was by the provision of vacuum devices for engaging the copy sheet and the master and separating such vacuum devices thereby separating the copy sheet from the master. These devices have not been satisfactory because of the complicated structures required for this purpose and it is an object of the present invention to overcome the problem of separating the master from the copy sheet.

Another object is to provide equipment to produce copies with the master and copy sheet in register at the leading edges thereof and to provide means for causing one sheet to be retarded with respect to the other, thereby offsetting the leading edges to provide for ease of separation.

Briefly, the present invention provides an exposing station including a cylindrical drum with a source of light therein and a reflector with belt means to move a sandwich of a master and a sensitive copy sheet over the surface of the transparent drum thereby exposing the sensitive copy sheet and thereafter guiding the sandwich to a concave curve inducing guide board which contacts the master applying a frictional force thereon as the copy sheet is fed forwardly to a guide plate adjacent the emerging end of the concave curve inducing guide board with gear means adapted to engage the leading edge of the copy sheet causing the copy sheet to be moved away from the master while causing the copy sheet to produce a hump which further moves the master away from the copy sheet permitting ease of separation thereof. There-

2

after the copy sheet is fed by the gear means to an extension of the belt means and thence by means of a pinch roller feeding the copy sheet to a processing station where the image is developed and fixed.

5 In the drawings:

FIGURE 1 is a schematic side elevation of the essential elements of the copying machine with the frame and driving means omitted.

10 FIGURE 2 is a fragmentary plan view of the machine shown in FIGURE 1 with parts broken away to show the structure thereof and showing the side frame members for supporting the belt guide and driving rollers, the gear means and the belts.

15 FIGURE 3 is a fragmentary schematic side elevation similar to FIGURE 1 showing the first contact of the leading edges of the master and the copy sheet with the curve inducing guide board.

20 FIGURE 4 is a similar view showing the leading edges of the master and sensitive copy sheet fed further along the curve inducing guide board.

25 FIGURE 5 shows the initial separation of the master from the copy sheet and illustrating one position of the slant guide plate to produce the desired initial contact with the gear means to obtain the humping action for further facilitating the separation of the copy sheet from the master.

30 Referring more particularly to the drawings, a pair of side frame members *a*, *a* rotatably support belt guide rollers 1, 2, 3, 5, and 4 over which rollers a plurality of belts 7 arranged in parallel relation transverse to the axes of the rollers pass to feed a master *b* and a copy sheet *c* of sensitive sheet material.

35 A cylindrical light housing 6 of transparent material is rotatably mounted between the frame members *a*, *a* with a source of light in the form of a lamp 8 mounted therein with a reflector 9 to direct the actinic rays through the master *b* and into exposing relation with respect to the copy sensitive sheet *c* as the sandwich of the master and the copy sensitive sheet pass over the surface of the cylindrical drum 6 by the feeding action of the belts 7.

40 A curve inducing guide board 10 having a concave cylindrical surface embracing the feed belt roller 1 receives the emerging sandwich of the master *b* and the copy sheet *c* as shown in FIGURE 3 and further feeding of the sandwich causes the master *b* to be frictionally retarded due to its contact with the concave surface of the curve inducing guide board 10 as shown in FIGURE 4, and further feeding to cause the sandwich to emerge from the upper edge of the curve inducing guide board 10 causes the sandwich to be fed into contact with the gear means 12 mounted on the shaft 11 rotatably mounted in the frame members *a*, *a*.

45 A guide plate 14 is positioned adjacent the exit end of the curve inducing guide board 10 being pivotally mounted on a shaft 15 supported by the frame members *a*, *a* to guide the leading edge of the copy sheet *c* into the spaces between the teeth 12' as clearly shown in FIGURES 1 and 5.

50 A shelf 13 positioned above the curve inducing guide board 10 is adapted to receive the master *b* as it separates from the copy *c*. A table 18 provided adjacent belt supporting roller 2 serves as a support for the sandwich of the copy sheet *c* and the master *b* as they are fed in the direction of the arrows as the belt 7 is operated around the belt guide rollers. Feed wheels 17 frictionally engage the belts 7 and/or the roller 4 and serve to feed the exposed copy sheet *c* between guide board 19 and guide board 19' to a developing station 20 where the image is developed and/or fixed, thereby producing a permanent copy.

55 70 The copy sheet *c* may have a tendency to curl in a downward curve as shown in full lines in FIGURE 1, or

it may have no tendency to curl, or it may have a tendency to curl upwardly. To compensate for any of these tendencies, the slat guide plate 14 may be adjusted to be substantially radial to the axis of shaft 11 or may be adjusted so that the plane of the slant guide plate is above or below the axis of shaft 11. This adjustment makes it possible to assure that the leading edge of the copy sheet c will enter the spaces between the teeth 12' of the gear means 12. The gear means 12 is rotated in the direction of the arrow shown in FIGURE 5 at a slower peripheral speed than the speed of the belts 7 and the leading edge of the copy sheet is positively engaged with the teeth of the gear means 12 causing a stoppage of the horizontal motion of the leading edge of the copy sheet c as the copy sheet c is fed by the belts 7 from the exposing housing 6, thereby causing the copy sheet to hump upwardly to a greater extent and causing the leading edge of the master to extend upwardly as shown in full lines in FIGURE 5 and further causing the master b to follow the upwardly curving dotted line shown in FIGURE 1 so that the natural motion thereof will place the master on the shelf 13, in any case the leading edge of the master is well separated from the copy sheet so that the operator can easily grasp the master and prevent it from following the copy sheet.

The copy sheet is then fed along the dotted line path c in FIGURE 1 between the feed wheels 17 and the belts and/or roller 4 between the guide boards 19, 19' to the developing and/or fixing station 20.

It will thus be seen that the present invention assures positive separation of the master or original from the copy sheet without requiring complicated expensive apparatus and without requiring special positioning of the master on the copy sheet.

What is claimed is:

1. Apparatus for exposing sensitive copy sheet material through a master and separating the copy sheet from the master comprising an exposing station, conveyor means to move a master and a copy sheet from the exposing station, a curve inducing guide board having a concave surface of substantial arcuate extent arranged with one end in the path of the master and copy sheet from the exposing station by the action of the conveyor means, the other end of said concave surface being spaced laterally away from the path of the master and copy sheet from the exposing station, a guide plate adjacent the other end of the concave surface to support the leading end of the master and copy sheet emerging from said concave surface with one end of said guide plate adjacent said other end of the concave surface of the guide board, gear means in the path of the master and copy sheet guided by said guiding surface of said guide plate, said gear means spaced from the other end of said guide plate, said master

and copy sheet being of sufficient length to extend from said conveyor means to said gear means whereby the leading edge of the copy sheet will engage between the teeth of the gear means and be caused to move transversely in a direction away from the supporting surface of said guide plate, means to drive said gear means so the peripheral speed thereof is much slower than the speed of the conveyor whereby the leading edge of the copy sheet will be arrested upon engagement with the gear means and the adjacent portion of the copy sheet will hump up in a direction above the guiding surface of the guide plate and cause the master to be moved away from the guide plate and the copy sheet whereby the leading edge of the master can be readily separated from the copy sheet and the copy sheet fed under the gear means for discharge for further processing.

5 2. The invention according to claim 1 in which the guide plate is movably mounted so the other end of the guide plate can be adjusted so the copy sheet can be guided directly toward the axis of the gear means or above the axis of the gear means or below the axis of the gear means.

10 3. The invention according to claim 1 in which a table for receiving the master is mounted adjacent the other end of said concave surface.

15 4. The invention according to claim 1 in which the exposing station includes a rotatable transparent drum surrounding a light source and the conveyor is belt means engaging the drum and guided by rollers so positioned that the belt means pass between the gear means and the drum to convey the copy sheet to the developing station.

20 5. The invention according to claim 4 in which a feed wheel is positioned adjacent one of the guide rollers for the belt means to cooperate with the belt means to frictionally feed the copy sheet for further processing.

25 6. The invention according to claim 5 in which a pair of guide boards are positioned in the path of the copy sheet emerging from the feed wheel and the belt means.
